UNITED STATES PATENT OFFICE

2,279,049

FREEZING EVAPORATOR

Walter Kleinow, Hennigsdorf, Kreis Osthavelland, Germany, assignor to General Electric Company, a corporation of New York

Application September 5, 1940, Serial No. 355,539
In Germany October 31, 1939

3 Claims. (Cl. 62—126)

My invention relates to evaporators for refrigerating machines.

In some refrigerating machines and particularly those provided for small household refrigerators, it is desirable that the cooling unit or evaporator should occupy a very small portion of the interior of the cooling compartment. The evaporator commonly provided for a household refrigerator includes a freezing shelf on which freezing trays or pans are supported in order that ice may be formed in the refrigerator. The shelf inherently reduces the free circulation of air over the surface of the evaporator and, furthermore, takes up a substantial portion of the available space. Household refrigerators may be provided with evaporators having only vertical walls which do not impede the circulation of air and are effective to provide efficient cooling of the food compartment. These evaporators, however, do not provide a support for freezing trays.

It is an object of my invention to provide a refrigeration evaporator having a substantially vertical freezing and air-cooling wall and an improved arrangement for retaining a freezing tray in close thermal contact with the vertical freezing wall.

For a better understanding of my invention, reference may be had to the accompanying drawing in which Figs. 1 and 2 are front and side views, respectively, partly in section, of a household refrigerator provided with an evaporator embodying my invention; Fig. 3 is an enlarged perspective view of the evaporator shown in Figs. 1 and 2; and Fig. 4 is an enlarged end view of a portion of the evaporator of Fig. 1 showing the arrangement of the freezing trays.

The evaporator illustrated on the drawing comprises generally a sheet-metal structure providing a single substantially vertical wall having formed therein a plurality of refrigerant-circulating passages and a gas-separating header. The evaporator is arranged near the center of the food compartment so that there may be a circulation of air downwardly along both sides of the evaporator, which provides efficient cooling of the cabinet air. In order to freeze water and other fluids to provide ice and frozen desserts, one or more freezing trays are employed which are constructed with connectors arranged to engage complementary connectors on the evaporator and to retain the trays in close thermal contact with the vertical freezing wall of the evaporator. When the trays are removed, the free circulation of air vertically along the evaporator wall is unimpeded.

Referring now to the drawing, in Figs. 1 and 2 I have shown a thermally insulated refrigerator cabinet 10 having a food storage compartment 11 cooled by an evaporator or cooling unit 12 arranged in the central portion thereof. The evaporator comprises a single vertical air-cooling and freezing surface arranged so that air may circulate downwardly over both sides thereof. Vaporized refrigerant is withdrawn from the evaporator through a suction line 13 and is compressed by operation of a motor-driven compressor within a casing 14; the casing is mounted on top of the cabinet and is provided with a plurality of heat-radiating fins 15. The compressed refrigerant is discharged into a condenser 16 where it is cooled and liquefied and flows to a float-valve chamber or liquid receiver 17. The liquid refrigerant is returned to the evaporator through a liquid line 18 upon operation of a float 20 actuated valve or other suitable flow-controlling mechanism in the receiver 17.

Within the food compartment 11, there are arranged a plurality of shelves 19 which extend outwardly from the walls and terminate short of the side walls of the evaporator 12 in order to provide unobstructed air paths on both sides of the evaporator. A shelf 20 extends across the compartment 11 below the evaporator and a suitable pan 21 may be supported on the shelf 20 to collect the moisture condensed on the evaporator 12 and which is melted during the defrosting operation.

In order to form ice in the cabinet, I provide one or more freezing trays 22 secured in close thermal contact with the vertical freezing wall of the evaporator 12 by means of suitable interengaging connectors; the connectors illustrated comprise hooks 23 secured to the ends of the trays 22 and lugs or pins 24 secured to the evaporator 12 near the ends of the trays. The construction and arrangement of the freezing trays are more clearly shown in Figs. 3 and 4. As shown in Fig. 3, the evaporator comprises two metal sheets 25 and 26 provided with complementary corrugations forming a header 27 and a plurality of depending refrigerant-circulating passages 28 communicating with the header through upper and lower manifolds 29 and 30 and end connections or conduits 31. The sheets 25 and 26 are welded together around their edges and between the corrugations, and the sheet 26 is folded or turned over the sheet 25 at its ends as indicated at 32. The lugs or pins 24 are welded or otherwise suitably secured to the edges of the

evaporator adjacent the folded portion 32 of the sheet 26.

As shown in Figure 4, the trays 22 lie closely adjacent the vertical side walls of the evaporator and against the circulating conduits 28 and 31, and the connectors 23 comprising sheet metal angles secured to the ends of the trays at 33 by welding, or in any other suitable manner, are provided with hook portions 34 which engage the reduced portions 35 of the pins 24 and are retained in place by heads 36 of the pins. The points at which the hooks 34 rest on the pins 24 are above the centers of gravity of the trays 22 and the trays tend to rotate about the connecting points and press the side walls of the trays against the sides of the evaporator wall, thereby assuring good thermal contact between the trays and the evaporator.

When water has been placed in the trays 22 and frozen by operation of the refrigerating machine, there will normally be a frozen bond between the tray and the evaporator due to the accumulation of condensed moisture, and this bond must be broken before the trays can be removed readily from their supports. I therefore construct the lower edge of each tray 22 so that the wall of the tray is spaced from the evaporator wall as indicated at 37. This leaves a recess within which may be inserted the point of a tool or lever 38 as indicated at 39. When the tool 38 is pressed downwardly, as indicated by the arrow, any frozen bond between the tray 22 and the wall of the evaporator 12 will be broken. The tray can then be lifted away from the pins 24 and removed from the refrigerator.

When the freezing trays are not required, they may be removed from their positions on the pins 24, whereupon the free circulation of air over the walls of the evaporator is unimpeded since it is necessary to provide no additional shelf or other structure which will restrict the circulation of air. This arrangement is of particular advantage when freezing is not required and when it is desired to operate the refrigerator at higher temperatures.

While I have illustrated and described my invention in connection with a household refriger-

ator, other applications will be apparent to those skilled in the art. I do not, therefore, desire my invention to be limited to the particular construction shown and described and I intend in the appended claims to cover all modifications within the spirit and scope of my invention.

What I claim as new and desire to secure by Letters Patent of the United States is:

1. An evaporator for a refrigerating machine having a substantially vertical freezing and air cooling surface, a freezing tray having a vertical side wall adapted to engage said freezing surface, and interengaging elements on said tray and on said evaporator adjacent the ends of said tray for detachably securing said tray in good thermal contact with said surface, whereby upon removal of said tray said freezing surface presents a substantially uninterrupted area affording a free circulation of air over said surface.
2. An evaporator for a refrigerating machine having a substantially vertical freezing surface, a freezing tray having a vertical side wall adapted to engage said freezing surface, interengaging connectors on said evaporator and on said tray for supporting said tray and for holding said tray in good thermal contact with said freezing surface, said connectors on said tray and evaporator being arranged to engage one another above the center of gravity of said tray whereby said tray tends to rotate about said connectors and press the vertical side wall thereof against said freezing surface.
3. An evaporator for a refrigerating machine having a substantially vertical freezing surface, a freezing tray having a vertical side wall adapted to engage said freezing surface, and interengaging connectors on said evaporator and on said freezing tray for supporting said tray and for holding said tray in good thermal contact with said freezing surface, the side wall of said tray adjacent said freezing surface having a portion near the bottom thereof spaced from said freezing surface whereby a prying tool may be inserted between said surface and said tray and operated to break a frozen bond therebetween.

WALTER KLEINOW.
